UNITED STATES PATENT OFFICE

158,050

INSULATED CONTAINER FOR FOOD

Houghton W. Clarke, Bronxville, N. Y.

Application August 16, 1946, Serial No. 132,599

Term of patent 14 years

(Cl. D58—17)

To all whom it may concern:

Be it known that I, Houghton W. Clarke, a citizen of the United States, residing at Bronxville, New York, have invented a new, original, and ornamental Design for an Insulated Container for Food, of which the following is a specification, reference being had to the accompanying drawings, which form a part thereof, in which:

Figure 1 is a perspective view of the top and front of an insulated container for food showing my new design,

Figure 2 is a perspective view of the rear and bottom thereof, and

Figure 3 is a perspective view of the interior thereof as it appears in separated position.

I claim:

The ornamental design for an insulated container for food, substantially as shown.

HOUGHTON W. CLARKE,
